UNITED STATES PATENT OFFICE.

CARLYLE D. BIDWELL, OF MILWAUKEE, WISCONSIN, ASSIGNOR, BY MESNE ASSIGNMENTS, TO INTERNATIONAL HARVESTER COMPANY, A CORPORATION OF NEW JERSEY.

PREHEATER FOR FURNACES.

1,382,757.

Specification of Letters Patent. Patented June 28, 1921.

Application filed September 13, 1918. Serial No. 253,973.

To all whom it may concern:

Be it known that I, CARLYLE D. BIDWELL, a citizen of the United States, residing at Milwaukee, in the county of Milwaukee and 5 State of Wisconsin, have invented certain new and useful Improvements in Preheaters for Furnaces, of which the following is a full, clear, and exact specification.

This invention relates to furnaces and especially to oil burning furnaces.

An object of the invention is to increase the efficiency of such furnaces by means of a more perfect combustion of the fuel.

Heretofore it has been very difficult to obtain a uniform and complete burning of the fuel where oil was used under the varying heat conditions required of the average forge shop furnace. Incomplete combustion of fuel in an oil burning furnace results in a 15 smear of oil around the furnace, a coating within the furnace of oil and a collection of carbon on the furnace walls, and often the production of clouds of dense, foul smoke from the furnace, which renders the air unfit to breathe and makes ventilation very 20 difficult.

Another object is to provide means for recovering some of the heat of the waste gases and return some of this heat to the furnace, 30 at the same time affording a protection to the workman and rendering the cooled waste gases easier to handle and lessening the labor required to ventilate the furnace room.

With these and other objects in view, my 35 invention consists in the combination and arrangement of parts herein described and covered in the appended claims. Reference is now had to the drawings in which,—

Figure 1 is a front elevation of a furnace 40 showing the pre-heating coils in place and the cooling coils and metal of the cooling front partly broken away;

Fig. 2 is an end elevation of the furnace;

Fig. 3 is a plan view of the furnace;

Fig. 4 is a section on the line 4—4 of Fig. 45 1; and

Fig. 5 is a section on the line 5—5 of Fig. 4.

The furnace 10 which I have chosen to 50 illustrate in connection with my invention, consists of the front wall 11 having a single opening 12 on a level with the floor 13 of the furnace, and the end walls 14, the back wall 15, the top 16, and bottom 17. The furnace 55 is supported on legs 18.

The furnace has the usual features of the oil burning furnace having a nozzle at each end. Air is supplied through a pipe 19 and by branches 20 to the headers 21. As shown in Fig. 4 each header has a partition 22 60 dividing the header into inlet and outlet chambers 21^a and 21^b. These are connected by a series of outgoing pipes 23, return bends 24 and return pipes 25. These pipes are arranged in the headers in multiple so that the 65 air can leave the chamber 21^a through any one of the pipes 23 and return to the chamber 21^b through the corresponding pipe 25.

These pipes 23 and 25 are placed in the path of the hot furnace gases so that the 70 gases must pass around the pipes as the gases leave the opening 12. After the hot air has made the circuit of the pipes 23 and 25 to the chamber 21^b, it then passes through the pipe 26 and the valve 27 to the nozzle 28. 75

Oil is supplied through the pipe 29 (see Fig. 1), is passed down through the coil 30 in the chamber 21^b where it is heated by the pre-heated air and is then led by the pipe 31 to the spray nozzle 28. On this furnace 80 which has two nozzles the coils for pre-heating the air and oil are substantially duplicates.

The hot gases are prevented from blowing 85 out into the operator's face by means of a long series of air jets from holes 32 in the pipe 33 which is placed in front of the furnace and below the opening 12. This pipe is supplied with air from the main air supply pipe 19. The effect of these jets is to 90 cause the hot waste gases to pass up between the front of the furnace and the protecting front. This consists of a steel plate 34 backed with a series of pipe coils 35. Water is forced through these coils and out through 95 the overflow pipe 35' where it is caught in the basin 36 and led to a drain. The water pipes and metal front are carried on supports 37 and the space surrounding the pipes is filled with a material 38 of low heat conductivity, such as asbestos. 100

The operator is thus protected by the front 34 from the direct radiation of heat from the furnace, and from the hot furnace gases which are caused to flow up behind the protecting front, as well as from injury due to direct contact with the water cooled front. 105

While I have shown and described but a single embodiment of my invention, it is to be understood that it is capable of many 110

modifications. Changes, therefore, in the form and arrangement may be made without departing from the spirit and scope of the invention as disclosed in the appended 5 claims.

What I claim as my invention and desire to secure by Letters Patent is:

1. In a furnace having a nozzle at the end and a charging door at the side, the combination of a water-cooled shield in front of 10 said door, a passage between said shield and said furnace, means for causing the waste gases to pass up between the shield and the furnace, and means for extracting heat from 15 the waste gases in said passageway and for returning the heat to the nozzle.
  2. In a furnace, the combination of a passageway for waste gases, one of the walls of 20 said passageway being cooled, means in said passageway for extracting heat from the waste gases, and means for utilizing part of 25 the heat so extracted for preheating the air and fuel for the furnace.
  3. In a preheating unit for air and oil, a header having a plurality of chambers for 30 the passage of air, a plurality of air heating tubes connecting said chambers, and oil heating means in one of said chambers.
  4. A water cooled front for furnaces, comprising a sheet metal screen and water coils 35 arranged behind said screen, and means for passing water through said coils and material of low heat conductivity surrounding said water coils.
  5. In a furnace having a charging door, the combination of a shield in front of said door and spaced from the furnace to provide 40 a passage for the waste gases, means for extracting heat from the waste gases, said means comprising a header having a plurality 45 of chambers at one side of the waste gas passage, and means connecting the chambers and extending into the passage.
  6. In a furnace having a charging door, 50 the combination of a shield in front of said door and spaced from the furnace to provide a passage for the waste gases, means for extracting heat from the waste gases, said means comprising a header having a plurality 55 of chambers at one side of the waste gas passage, means connecting the chambers and extending into the passage, and means to circulate a fluid through said chambers and connecting means.
  7. In a furnace having a charging door, 60 the combination of a shield in front of said door and spaced from the furnace to provide a passage for the waste gases, means for extracting heat from the waste gases, said means comprising a header having a plurality 65 of chambers at one side of the waste gas passage, means connecting the chambers and
- extending into the passage, and fuel heating means in one of said chambers.
8. In a furnace having a charging door, 65 the combination of a shield in front of said door and spaced from the furnace to provide a passage for the waste gases, means for causing the waste gases to pass upward between the shield and furnace, means for extracting heat from the waste gases, said means comprising a header having a plurality 70 of chambers at one side of the waste gas passage, and means connecting the chambers and extending into the passage.
  9. A preheater for furnaces having a fuel nozzle comprising, a header having a plurality of chambers, means for supplying a fluid to be heated to one of said chambers, a fuel heating coil in a second chamber, conduits connecting said chambers and adapted 75 to be heated by the waste gases from the furnace whereby the fluid supplied to the first chamber will be heated and will in turn heat the fuel coil in the second chamber, and means for conducting the heated fluid and fuel to the fuel nozzle of the furnace.
  10. In a furnace having a charging door, the combination of a shield spaced from said door to provide a passage for the waste 80 gases, means for causing the waste gases to pass upward through the passage, means for cooling the rear side of said shield, a header at each side of the shield, means for supplying a fluid to the headers to be heated, 85 conduits connected to the headers and extending into the passage for waste gases whereby the fluid will be heated, fuel heating means in one of said headers, a fuel nozzle for said furnace, and means for conducting the heated fluid and fuel to said fuel nozzle.
  11. In a furnace having a charging door, the combination of a shield in front of the door and spaced from the furnace to provide 90 a passage for waste gases, a source of air supply under pressure, air-heating means in said passageway, means for directing a flow of air upward through said passageway and means connecting said source of air supply to the air heating means and to the means for directing a flow of air.
  12. In a furnace having an open charging door, the combination of a shield in front of 95 said door spaced from the furnace to provide a passage for waste gases, means for cooling the shield, air heating means for said passage, means for directing a flow of air through said passage and separate means connecting said source of air supply with 100 the air heating means and the directing means.

In testimony whereof I affix my signature.
CARLYLE D. BIDWELL.
